Robert H. Wendt Inventor

UNITED STATES PATENT OFFICE

167,919

INFLATABLE BURRO FOR WATER SPORT

Robert H. Wendt, Evanston, Ill.

Application July 24, 1951, Serial No. 15,999

Term of patent 14 years

(Cl. D34—15)

To all whom it may concern:

Be it known that I, Robert H. Wendt, a citizen of the United States, residing at Evanston, in the county of Cook and State of Illinois, have invented a new, original, and ornamental Design for Inflatable Burro for Water Sport, of which the following is a specification, reference being had to the accompanying drawing, forming a part hereof.

Fig. 1 is a side elevational view of an inflatable burro for water sport, showing my new design;

Fig. 2 is a top plan view;

Fig. 3 is a front elevational view.

I claim:

The ornamental design for an inflatable burro for water sport, as shown.

ROBERT H. WENDT.
